US0D1076494S

(12) **United States Design Patent** (10) **Patent No.:** **US D1,076,494 S**
(45) **Date of Patent:** **** May 27, 2025**

(54) **MODULAR FURNITURE ASSEMBLY WITH BASE AND UPRIGHT MEMBER**

(71) Applicant: **THE LOVESAC COMPANY**, Stamford, CT (US)

(72) Inventors: **Shawn D. Nelson**, Washington, UT (US); **David M. Underwood**, Hurricane, UT (US)

(73) Assignee: **The Lovesac Company**, Stamford, CT (US)

(**) Term: **15 Years**

(21) Appl. No.: **29/806,384**

(22) Filed: **Sep. 2, 2021**

(58) **Field of Classification Search**

USPC D6/334, 335, 367, 378, 381, 716, 716.1

(57) **CLAIM**

The ornamental design for a modular furniture assembly with base and upright member as shown and described.

DESCRIPTION

The sole FIGURE is a perspective view of a modular furniture assembly with base and upright member.

The even spaced broken lines depict portions of the article that form no part of the claimed design. The dot-dash-dot broken lines depict boundary lines indicating the boundary of the claimed design.

The stippling illustrated in the sole FIGURE depicts a contrast in material.

1 Claim, 1 Drawing Sheet

Related U.S. Application Data

13/164,721 is a continuation-in-part of application No. 12/484,931, filed on Jun. 15, 2009, now Pat. No. 7,963,612, which is a continuation-in-part of application No. 11/449,074, filed on Jun. 8, 2006, now Pat. No. 7,547,073, which is a continuation-in-part of application No. 11/149,913, filed on Jun. 10, 2005, now Pat. No. 7,213,885.
